DESIGN FOR AN ELECTRIC SADIRON

Clarence Karstadt, Chicago, Ill., assignor to Birtnan Electric Company, a corporation of Illinois

Application June 14, 1944, Serial No. 113,992

Term of patent 14 years

(Cl. D49—6)

To all whom it may concern:

Be it known that I, Clarence Karstadt, a citizen of the United States, residing at Chicago, in the county of Cook and State of Illinois, have invented a new, original, and ornamental Design for an Electric Sadiron, of which the following is a specification, reference being had to the accompanying drawing, forming a part thereof, in which:

Fig. 1 is a side elevational view of an electric sadiron showing my new design; Fig. 2 is a top plan view thereof; and Fig. 3 is a front elevational view thereof.

I claim:

The ornamental design for an electric sadiron, as shown.

CLARENCE KARSTADT.
